UNITED STATES PATENT OFFICE.

CHARLES H. CLARK, OF WESTFIELD, MASSACHUSETTS.

WHIP CONSTRUCTION.

1,250,561.

Specification of Letters Patent. Patented Dec. 18, 1917.

Application filed April 16, 1917. Serial No. 162,476.

To all whom it may concern:

Be it known that I, CHARLES H. CLARK, a citizen of the United States of America, residing at Westfield, in the county of Hampden and State of Massachusetts, have invented certain new and useful Improvements in Whip Constructions, of which the following is a specification.

This invention relates to whips and more particularly to an improved construction for the eye or lash loop of a whip.

The problem of constructing the lash loops of whips is one which has perhaps received more attention on the part of whip manufacturers than any other problem encountered in whip manufacture. The lash loop has come to be commonly known and recognized as the weak point in the whip, and from experience it has been found that the 20 majority of whips fail at the lash loop and would otherwise be good for a considerably longer period of useful service had the lash loop not been of faulty construction. Countless experiments have been made and various 25 constructions put forth with the object of improving the lash loop and, although the whip art has long been developed in other respects, the lash loop construction of the whip has not heretofore, it is believed, been 30 satisfactorily worked out.

This invention has for its object to provide an improved lash loop construction or loop reinforcement for whips wherein a looped member, substantially of hair pin 35 shape, is bound to the core of the whip with the loop protruding beyond the tip of the whip to form a lash loop, the material of said member being characterized in that it is strong, flexible, and resilient and does not 40 add materially to the bulk of the whip and in that it may be joined to the whip core with a strong and effective bond.

The invention, in an embodiment at present preferred, is shown for illustrative purposes in the accompanying drawings, in which:

Figure 1 is an elevational view of the tip end of a whip embodying the invention;

Fig. 2 is an enlarged cross sectional view 50 taken on the line 2-2 of Fig. 1; and

Fig. 3 is an elevational view of the improved loop forming part shown as removed from the whip.

Referring to these drawings in detail, the 55 whip body itself may be made up in any suitable manner. The core 5 of the whip (pref-

erably of twisted rawhide) tapers gradually near the tip end thereof and terminates with a blunt point. Below the tip end of core 5, other materials such as ratan or the like 60 may be applied around the core in the usual manner, and the whole is covered with a suitable braided covering 6.

The lash loop or eye 7 of the whip is formed by applying a looped member 8, bent 65 substantially in the form of a hair pin to the core 5 before the latter is braided. The looped member 8 is relatively long compared with the length of the eye 7 to be formed, and the long sides of the member 70 are applied to the core at diametrically opposite points, as indicated in Fig. 1, so that only a small portion of member 8 protrudes beyond the tip of core 5. The protruding and eye forming portion of member 8 preferably 75 has a braided covering 9 which may be applied in any suitable manner but which may advantageously be applied by slipping a tubular woven fabric or stocking on the looped end of member 8 before the latter is 80 applied to core 5. The covering 6 is then braided over the member 8 and core 5 to firmly bind the former to the latter, and covering 6 preferably extends only to the lower part of eye 7 and should slightly overlap the tubular braided covering 9.

The loop forming member 8 is formed from a hard and hornlike material, such as a quill, for example, and such material is one of the important features of my invention 90 in the particular use to which it is put. The hollow stalk of a feather quill may be split longitudinally into several parts, and each one of these parts may be thereafter utilized as a loop forming member. Aside from 95 the natural characteristics inherent in the feather quill which make it particularly desirable and advantageous for the present purposes, there is also an important structural advantage obtained. The fact that a 100 feather quill is originally of tubular form is important for, when it is slit into several parts as described, each has an appreciable amount of concavity. Thus, the member 8 is not a flat strip but is of curved cross sectional shape. Those surfaces of member 8 105 which are applied to core 5 are concave and readily mate with the convex surface of the core, as illustrated in Fig. 2. Thus, the quill is advantageous as a material for lash loop 110 construction, on account of its natural concavity and its tendency to conform readily

to the shape of the core. The member 8, therefore, has no tendency to spring away from the core and thereby gradually loosen the braided covering 6 since it does not originally have to be forced in place but on the contrary naturally accommodates itself to the shape of the core.

The quill of a feather possesses certain natural characteristics which make it especially suitable for use in constructing the lash loop of a whip. It is a tough, horn-like material possessing a considerable amount of tensile strength. It is thin, averaging perhaps about one sixty-fourth of an inch in thickness, and, as is well known, it is remarkably light and strong. The material of a feather quill is non-corrodible, non-rustable, and is not adversely affected by water or exposure to the elements. The quill is furthermore flexible and also resilient to the necessary degree for use in whips for the purpose described.

It has been shown that the cross sectional shape of the split quill is such that the latter may be readily and tightly drawn to the core so that the inner surface of the quill is in intimately close contact with the core. This, as has been pointed out, is of importance in providing a strong effective bond between the core and quill by the fabric covering applied therearound and improves the appearance of the whip end. It should also be noted that, although the outer surface of a feather quill is fairly smooth, the inner surface is provided with a plurality of ridges and commonly there is a rather rough deposit of chalk-like material thereon. The ridges and the rough deposit described further add to the strength of the bond between the core and the quill for all the irregularities in the inner surface of the quill tend to dig into the core of rawhide, for example, when the quill is drawn tightly to the latter by the fabric covering 6 and to resist relative displacement of the core and quill.

It has also been pointed out that the quill possesses the requisite degree of flexibility and resiliency for use as a lash loop for a whip. The remaining advantages of the quill as used for a lash loop are due to the fact that the quill is exceedingly light and thin and possesses a remarkable degree of tensile strength in proportion to its weight. Thus, the split quill applied to the whip core as described does not add materially to the weight of the whip and more particularly does not add an appreciable amount of weight to the tip end of the whip where ad-

ditional weight is manifestly undesirable. Moreover, since the quill is thin and is comparable in thickness to the thickness of the fabric covering, the increase in diameter of the tip end of the whip due to the use of the quill is not readily detected. The quill may be applied to a whip, as described, without detracting from the appearance of the whip.

A neat appearing joint can readily be made and at a point of the whip where the ordinary additions to the core are most apparent for the tip end of the core is generally less than an eighth of an inch in diameter. Moreover, the tensile strength of the quill is high when compared with that of an equal weight of most other materials heretofore used as lash loop reinforcements. Steel, of course, is high in tensile strength but cannot be readily bound to the core in such a manner that all its tensile strength may be utilized, and such material tends to cut through the fabric or rust and spoil the fabric. Thus, the necessary tensile strength for the lash loops may be obtained without adding materially either to the bulk or the weight of the whip, which is a most important advantage in practical whip construction.

Thus, an improved lash loop construction has been provided for whips which is characterized by strength without appreciably increasing the weight or size of the tip end of a whip and which is further characterized by a strong and effective bond with the core of the whip. The invention has been described in a preferred form for illustrative purposes, but the scope of the invention is defined by the appended claims rather than by the foregoing description.

What I claim is—

1. A whip, having a core of substantially circular cross sectional shape, a lash loop member consisting of split quill bent substantially the shape of a hair pin, the ends of which overlap said core and have concave surfaces adapted to conform to and closely fit the convex surface of the core, and means to bind said ends to the latter.
2. A whip having a central core of substantially circular cross sectional shape, a lash loop consisting of split quill bent substantially in the shape of a hair pin, the ends of which overlap said core, said quill having concave surfaces adapted to conform to and closely fit the convex surface of said core, and an outer braided covering for the loop and like covering for the core to bind the ends of the quill thereto.

CHARLES H. CLARK
